UNITED STATES PATENT OFFICE

EDWARD B. WILEY, OF SOMERVILLE, MASSACHUSETTS

FLAG HOLDER

Application filed February 10, 1932. Serial No. 592,073.

My invention relates to flag holders and particularly to the class in which either or both staff and holder are of tubular nature.

The object of my invention is to provide a combined staff and holder for automobiles, signalling and the like, which is adaptable to protect a flag from the weather when not in use.

A second object is to provide a telescopic holder, within which the flag may be enclosed when not in use.

A further object is to provide a holder of convenient size which may be attached to a suitable support, and readily detached, and stored in relatively small space, or readily transported without exposure of the flag to the weather or to dust.

My invention consists in the novel character of holder I employ and the means I employ to protect the flag and to secure the holder to an automobile buffer.

With my invention, the flag holder is adapted for attachment to the buffer of an automobile, or by the substitution of suitable fastening means, may be secured to a wheel guard or may be used for manual signaling, the flag being withdrawn into an element of the holder which in turn may be telescoped, and when so telescoped, whether or not the staff be exposed to the elements, the flag is protected.

In the accompanying specifications and claims and the drawing forming a part thereof, I have described and illustrated a preferred embodiment of my invention, but do not confine myself to this particular form, as modifications may be introduced within the scope of the appended claims.

In the drawing:

Fig. 1 is a sectional elevation showing the preferred embodiment of my invention in operative relation with the buffer bars of an automobile.

Fig. 2 is a fragmental elevation showing the upper member of the holder and cap and the relation of the flag and slot in such member.

Fig. 3 is a sectional elevation of the holder in telescoped position with flag enclosed, and fastening means released.

Fig. 4 is a sectional plan of the holder on line 4—4, Fig. 3.

Referring to the drawing, the tubular element 10 is provided with a gland 11 secured to one end.

In this embodiment, I have shown an element 12 secured to the other end, and in which is hinged at 13 fastening means which I will presently describe. This end of the staff element may be provided with a base 12' for use on the wheel guard of an automobile or for use as a standard, or a closure cap not shown but of obvious character, may be used when the device is used in connection with manual signaling. Slidable axially within the tube and extending through the gland 11 is a second tubular element 14, having a plug 15 slidable on the inner walls of the element 10 and rigid with the element 14. The upper end of the element 14 is threaded at 16 and tapped to engage this end is a second gland 17, through which extends a neck 18 of the flag staff 19 which is provided with an enlarged portion 20 adapted to engage the surface 21 of the gland 17 and limit in one direction the axial movement of the staff 19 relative to the element 14.

The neck 18 is shouldered and the reduced portion threaded at 22 to engage the nut 23, the neck being rotatable in the gland 17 and the nut 23 functioning not only as a means for limiting the axial movement of the neck in the gland, but also as a means for turning the whole staff 19 to which the flag A may be attached by any suitable means, one means being such as shown, in which rivets 25 passing through the flag and staff, secure the flag thereto. The plug 15 is formed axially with a socket 26 and the staff 19 is shouldered, the reduced neck 27 being journalled in the socket and the shoulder bearing on the end of the plug. Opposite the flag in one wall of the element 14 is a slot 28 through which the flag may be drawn to expose it and when not required for use it may be wound about the staff 19 by turning the nut 23.

To retain the tubular elements in operative position as in Fig. 1, any suitable means may be employed, one such means including a plunger 29 axially slidable in the plug 15 normal to its axis, one end being pressed against

the inner wall of the element 10 by a spring 29 seated in the plug. This plunger is adapted to engage with a perforation 30 in the walls of the element 10, near the gland 11, 5 and the end is so formed and the axial movement so limited, that it may be released by the relative rotation of the tubular members. Both the gland 17 and the nut 23 are provided with respective over hanging portions 31, and 10 32 forming annular ridges, the former overlapping the gland 11 when the member 14 is telescoped and the latter overlapping the gland 17, together protecting the flag from the elements when the staff is telescoped.

15 My invention also includes the means for securing the staff to the buffer of an automobile, which I will now describe. Hinged to the element 12 at 13 is a stub 35 to which is secured a tubular element 36, the opposite 20 end being perforated to form a slide bearing for the stem 37, to the inner end of which is secured the plunger 38 slideable axially in the tube and forming an abutment against which the spring 39 reacts at one end, the other re- 25 acting against the tube end 40, and operating to yieldingly press the plunger and stem toward the hinge. To the other end of the stem is secured the element 41 which is formed with projections adapted to engage the forks 30 43 of the element 44 slideable on the staff element 10.

The element 44 may be moved axially on this tube to any position, and the distance between the projections 42 and the hinge 13 35 is predetermined to agree with the over-all width of the buffers of the automobile, a reasonable variation being permissible and provided for by compression of the spring 39.

The element 12 being engaged with the 40 lower edge of the buffer bar 45 and the element 44 with the upper edge of the buffer bar 46, the spring 39 is compressed by applying force axially on the stem 37, and the projections are engaged with the forks 43, thus 45 firmly securing the staff to the buffers in a manner which may be readily released.

Having thus described my invention, I claim:

50 1. A flag support having a tubular staff member within which a flag may be withdrawn, and a tubular supporting member within which the staff member may telescope; and means secured to the end of the staff member adapted to overlap the end of the 55 supporting member when in telescoped position, for the purpose of protecting the enclosed flag from the elements.

60 2. A flag support having a tubular staff member provided with a slot in the wall thereof, and a spindle rotatable axially within the tubular staff member and to which the flag may be attached to extend through the slot, and in combination with said staff member a tubular supporting member within 65 which the staff member may telescope; and

means secured to the outer end of the spindle and rotatable therewith for winding the flag thereon within the staff member.

3. A flag support having a tubular staff member provided with a slot in the wall 70 thereof, and a spindle rotatable axially within the tubular staff member and to which the flag may be attached to extend through the slot, and in combination with said staff member a tubular supporting member within 75 which the staff member may telescope; and means secured to the outer end of the spindle and rotatable therewith, and adapted to overlap the end of the supporting member when in telescoped position.

EDWARD B. WILEY.
